United States Patent Office

Des. 211,343
Patented June 11, 1968

211,343

FAUCET SPOUT

Allan F. Jones, Jamestown, N.Y., assignor to Period
Brass, Inc., Jamestown, N.Y., a corporation of Texas

Continuation of design application Ser. No. 87,555,
Oct. 18, 1965. This application Feb. 9, 1967, Ser.
No. 6,221

Term of patent 14 years

(Cl. D23—23)

FIG. 1

FIG. 2

FIG. 1 is a side elevational view of a faucet spout showing my new design;

FIG. 2 is a plan view thereof.

This application is a continuation of my earlier co-pending application Ser. No. D. 87,555 filed Oct. 18, 1965, and now abandoned.

I claim:

The ornamental design for a faucet spout, as shown and described.
